RAZORS

Clarence A. Pinkham, Douglaston, and Bartholomew A. Holohan, Kew Gardens, N. Y., assignors to Nelpin Manufacturing Company, Inc., Long Island City, N. Y., a corporation of New York

Application July 7, 1953, Serial No. 366,474

10 Claims. (Cl. 30—68)

This invention relates to a novel safety razor having a body arranged for gripping in the user's hand, and not requiring a projecting handle. The invention razor is particularly designed for dry shaving of excess, unwanted hair from the limbs and arm pits.

The usual safety razor comprises a body having an elongated projecting handle and a head or other guard means arranged to clamp a razor blade in predetermined relation on the razor body with the blade edges at least partly exposed for cutting engagement with the hairs. These razors are designed particularly for shaving of the face where the angle of the razor blade to the skin and hair is not only important, for safety and comfort, but also difficult to control due to the varying facial contours. Experience has indicated that the blade angle can be most effectively controlled and maintained by providing an elongated handle extending substantially normal to the general plane of the razor blade.

Safety razors have become increasingly popular with women for removal of excess or unsightly hair from the limbs and armpits, particularly prior to dressing in sleeveless gowns or before donning sheer stockings. The usual projecting handle type of safety razor can be used for these purposes but is clumsy to handle and difficult to maneuver, particularly as such shaving of the limbs, etc., is done only at infrequent intervals and not as part of a daily routine. On the other hand, most men shave daily or every other day and thus become accustomed to handling the razor, so that proper positioning of the handle becomes more or less automatic.

In view of the foregoing, there has long been a need for a simple, efficient razor particularly designed for use by women in dry shaving hair from the limbs, etc., and which is easy and non-complicated to handle.

To this end, the present invention provides a safety razor which is characterized by the absence of the usual handle and comprises a body which can be readily gripped in the hand to draw the blade over the skin. A feature of the razor is the readily and easily effected assembly and disassembly of its parts.

More particularly, the body has a longitudinally recessed wall with transversely spaced blade engaging projections against which the blade is held by a removable head or guard shaped to deform the blade into the recess with the blade edges at a predetermined angle. The guard has blade positioning abutments and a post projectable into the razor body. This post has latching means on its free end engageable with a releasable latching element movably mounted in the razor body. The guard is automatically latched to the body by positioning the guard over a blade in the body wall recess and forcing the guard toward the body to interengage the spring biased latching element with the latching means on the guard post.

For an understanding of the invention principles, reference is made to the following description of a typical embodiment thereof as illustrated in the accompanying drawing.

2

In the drawing:

Fig. 1 is a perspective view of the invention safety razor;

Fig. 2 is a plan view of the razor body with the top or outer wall removed;

Fig. 3 is a longitudinal sectional view on the line 3—3 of Fig. 2;

Figs. 4 and 6 are transverse sectional views on the correspondingly numbered lines of Fig. 3;

Fig. 5 is a view similar to Fig. 2 with the guard engaging latching element removed;

Fig. 7 is a perspective view of the guard; and

Fig. 8 is a perspective view of the latching element.

Referring to the drawing, the razor 10 of the invention includes a double edge razor blade 15 releasably held in proper conformation on a body 20 by a removable guard 40. Blade 15 is formed with the usual positioning openings 16 and 17.

The body is formed as a hollow casing including a top or outer wall 21 joined to an inner, blade-engaging wall 25 by the side walls 22 and end walls 23. Preferably, walls 22, 23 and 25 are molded as an integral, open-sided box, and wall 21 is joined thereto by pins or projections 24 secured in openings 26. The material of the body may be a metal or a suitable synthetic resin.

Inner wall 25 has a generally inverted V cross section, thus providing a recess 30 extending longitudinally of its outer surface. The longitudinal edges of the outer surface are recessed, as at 27, so that the remainder of the outer surface forms relatively raised blade engaging portions 28. When blade 15 is deformed into recess 30 by guard 40, as described hereinafter, its edges 18 extend substantially parallel to recesses 27 and terminate short of the longitudinal edges of wall 25.

As best seen in Figs. 3, 5, 6 and 7, wall 25 has a central, substantially circular opening 31 and elongated, central slots 32 in spaced relation to opening 31. A pair of transversely spaced guide walls 33 extend inwardly from wall 25, being integral therewith, to a point spaced somewhat from outer wall 21. Walls 33 have cylindrical portions 34 concentric with hole or aperture 31, and wing portions 36, 36 extend in parallel, spaced relation to each other from portions 34. Walls 33 act as guides for the guard post and the releasable latch element, as will be described. For a purpose to be described, one end wall 22 has a substantially rectangular notch 37 in its outer edge, and the opposite end wall 22 has a recess 38 in its inner surface extending inwardly from its outer edge.

Guard or head 40 comprises an elongated body 41 having bevelled longitudinal edges 42 and a central rib 43. The outer surface of body 41 is convexly curved transversely of the body, as at 44. A central, substantially cylindrical post 45 projects perpendicularly from rib 43, and substantially rectangular razor blade locating lugs 46 project from the rib in longitudinally spaced relation to post 45. The free end of post 45 carries latching means in the form of radial lugs 47 having double bevelled outer ends 48.

When guard 40 is assembled to the body 20 with a blade 15, post 45 enters blade aperture 16 and wall aperture 31, and lugs 46 project through blade apertures 17 and into slots 32, thus locating blade 15 on the razor. The bevelled edges 42 of body 41, and rib 43, bear against blade 15. Rib 43 deforms blade 15 into recess 30, with edges 18 clamping the blade against blade engaging portions 28 of wall 25.

The guard 40 and blade 15 are releasably latched to body 20 by a latching element 50. This latching element, as best seen in Figs. 2, 3, 4, 6 and 8, comprises a generally flat bar having a leg 51 engageable through notch 37 and formed with an inturned operating end 52. The inner end of leg 51 is continued as a pair of rails 53 transversely

spaced by a distance substantially equal to the diameter or thickness or diameter of post 45. The innermost ends of rails 53 are integrally joined by an inturned lug portion 54 having a latching lug 55 having a double bevelled outer end 56. Projecting from the other side of lug 54 is a spring seating pin 57 engageable in one end of a coil spring 60 having its opposite end seated in recess 38. Coil spring 60 biases latching bar 50 outwardly, thus moving latching lug 55 somewhat into the cylindrical space defined by wall portions 34. Latch bar 50 and spring 60 are positioned in place before outer wall 21 is assembled to body 20. The upper edges of walls 33 cooperate with wall 21 to guide bar 20.

When guard 40 is pressed against a blade 15 in recesses 40 and post 45 projected through opening 31, the bevelled edges 48 of a lug 48 cooperate with the bevelled edge 56 of lug 55 to force bar 50 inwardly, compressing spring 60. As lugs 47 pass beyond lug 55, spring 60 forces bar 50 outwardly to engage lug 55 beneath the adjacent lug 47 to releasably latch guard 40 to body 20. By pressing in-turned lug 52 inwardly, the latching engagement is released so that the blade and guard may be disassembled from body 41.

In use, body 20 is merely gripped in the hand and moved in either or both directions, by short or long strokes transversely of the length of the blade, thereby drawing the respective or both blade edges over the section of the skin acted upon for cutting the hair projecting therefrom, irrespective of whether unidirectional or reciprocating strokes are applied by the user. By virtue of the locational disposition of the blade and the respective blade edges on the body as shown and described in the illustrated embodiment, both blade edges may be utilized for speedy cutting action by reciprocity of the body 20, without reversing the hand grip thereon.

While a specific embodiment of the invention has been shown and described in detail to illustrate the application of the invention principles, it will be understood that the invention may be embodied otherwise without departing from such principles.

What is claimed is:

1. In a safety razor, the combination comprising a casing having an inner wall, an outer wall, and side and end walls interconnecting said inner and outer walls, said casing being shaped to be grasped by the user's hand; the inner wall of the casing being formed with a recess extending longitudinally of its outer surface and having a substantially centrally disposed opening therethrough into the casing; said recess having transversely spaced angularly related and substantially flat razor blade engaging surfaces; a guard having a post extending therefrom for insertion through said opening, a central longitudinal rib engageable with the blade to deform the latter into said recess to lie against said blade engaging surfaces, and blade engaging portions spaced on either side of said rib and positioned to clamp the blade against said blade engaging surfaces; latch means on the free end of said post; and a releasable latching element movably mounted in said casing and engageable with said latch means when said guard is pressed into said recess to deform a blade into said recess.

2. In a safety razor, the combination comprising a casing having an inner wall, an outer wall, and side and end walls interconnecting said inner and outer walls, said casing being shaped to be grasped by the user's hand; the inner wall of the casing being formed with a recess extending longitudinally of its outer surface and having a substantially centrally disposed opening therethrough into the casing; said recess having transversely spaced angularly related and substantially flat razor blade engaging surfaces; a guard having a post extending therefrom for insertion through said opening, a central longitudinal rib engageable with the blade to deform the latter into said recess to lie against said blade engaging surfaces, and blade engaging portions spaced on either side of said rib.

and positioned to clamp the blade against said blade engaging surfaces; latch means on the free end of said post; and a releasable latching element movably mounted in said casing adjacent the inner surface of said outer wall and engageable with said latch means when said guard is pressed into said recess to deform a blade into said recess.

3. In a safety razor, the combination comprising a
casing having an inner wall, an outer wall, and side and
end walls interconnecting said inner and outer walls, said
10 casing being shaped to be grasped by the user's hand; the
inner wall of the casing being formed with a recess
extending longitudinally of its outer surface and having a
substantially centrally disposed opening therethrough into
the casing; said recess having raised transversely spaced
15 angularly related and substantially flat razor blade engag-
ing surfaces spaced inwardly of the longitudinal margins
of said inner wall; a guard having a post extending there-
from for insertion through said opening, a central longi-
tudinal rib engageable with the blade to deform the latter
20 into said recess to lie against said blade engaging surfaces,
and blade engaging portions spaced on either side of said
rib and positioned to clamp the blade against said blade
engaging surfaces; latch means on the free end of said
post; and a releasable latching element movably mounted
25 in said casing and engageable with said latch means when
said guard is pressed into said recess to deform a blade
into said recess.

into said recess.

4. In a safety razor, the combination comprising a
casing having an inner wall, an outer wall, and side and
end walls interconnecting said inner and outer walls,
said casing being shaped to be grasped by the user's hand;
the inner wall of the casing being formed with a recess
extending longitudinally of its outer surface and having a
substantially centrally disposed opening therethrough into
35 the casing; said recess having raised transversely spaced
angularly related and substantially flat razor blade engag-
ing surfaces spaced inwardly of the longitudinal margins
of said inner wall; a guard having a post extending there-
from for insertion through said opening, a central longi-
40 tudinal rib engageable with the blade to deform the latter
into said recess to lie against said blade engaging sur-
faces, and blade engaging portions spaced on either side
of said rib and positioned to clamp the blade against said
blade engaging surfaces; latching lugs projecting in op-
45 posed directions from the free end of said post; and a re-
leasable latching element movably mounted in said casing
and engageable with said latching lugs when said guard
is pressed into said recess to deform a blade into said
recess.

50 5. In a safety razor, the combination comprising a
casing having an inner wall, an outer wall, and side and
end walls interconnecting said inner and outer walls, said
casing being shaped to be grasped by the user's hand; the
inner wall of the casing being formed with a recess ex-
55 tending longitudinally of its outer surface and having a
substantially centrally disposed opening therethrough into
the casing; said recess having raised transversely spaced
angularly related and substantially flat razor blade engag-
ing surfaces spaced inwardly of the longitudinal margins
60 of said inner wall; a guard having a post extending there-
from for insertion through said opening, a central longi-
tudinal rib engageable with the blade to deform the latter
into said recess to lie against said blade engaging surfaces,
and blade engaging portions spaced on either side of said
65 rib and positioned to clamp the blade against said blade
engaging surfaces; latching lugs projecting in opposed di-
rections from the free end of said post; a latch bar mov-
able longitudinally of the inner surface of said outer wall
and having an operating portion projecting through an
70 end wall, said bar having an aperture arranged to receive
the free end of said post; a projecting lip extending into
said aperture adjacent an edge thereof, and engageable
with one of said lugs to latch said guard to said casing
in a position deforming a razor blade into said recess;
75 and means biasing said bar to the latching position.

6. A razor as claimed in claim 5 in which said inner wall is formed with inwardly projecting guide means for said post.

7. A razor as claimed in claim 5 in which said inner wall is formed with inwardly projecting guide means for said post and terminating short of said outer wall to form therewith guide means for said latch bar.

8. A razor as claimed in claim 5 in which the inner surface of said guard carries razor blade locating projections extendable through openings in said inner wall.

9. A razor as claimed in claim 5 in which said inner wall is formed with inwardly projecting guide means for said post, said lip is inwardly of the bar body, and said guide means include transversely spaced portions in embracing and guiding relation with said lip.

10

15

10. A razor as claimed in claim 5 in which said inner wall is formed with inwardly projecting guide means for said post, said lip is inwardly of the bar body, and said guide means include transversely spaced portions in embracing and guiding relation with said lip; said biasing means comprising a spring engaged between the inner end of said bar and the opposite end wall of said casing.
